Primary Examiner—Mitchell Siegel

(74) Attorney, Agent, or Firm—Banner & Witcoff, Ltd.

(57) CLAIM

The ornamental design for a portion of a golf club head, as shown and described.

DESCRIPTION

FIG. 1 is an elevational view of a portion of a golf club head showing my new design;

FIG. 2 is a perspective view thereof;

FIG. 3 is a top view thereof; and,

FIG. 4 is a bottom view thereof.

The broken line showing of the remainder of the golf club head is for illustrative purposes only and forms no part of the claimed design.
